US0D1042454S

(12) **United States Design Patent** (10) Patent No.: **US D1,042,454 S**
(45) Date of Patent: ** Sep. 17, 2024

(54) **MOBILE ELECTRONIC DEVICE**

(71) Applicant: **Amazon Technologies, Inc.**, Seattle, WA (US)

(72) Inventors: **Christopher Clive Jones**, San Francisco, CA (US); **Gregory Ross Katz**, San Francisco, CA (US); **Quinn Huffstetler**, San Francisco, CA (US); **Gregory Germe**, Orinda, CA (US)

(73) Assignee: **Amazon Technologies, Inc.**, Seattle, WA (US)

(**) Term: **15 Years**

(21) Appl. No.: **29/918,527**

(22) Filed: **Nov. 28, 2023**

Related U.S. Application Data

(63) Continuation of application No. 29/777,275, filed on Apr. 5, 2021, now Pat. No. Des. 1,014,452.

(57) **CLAIM**

The ornamental design for a mobile electronic device, as shown and described.

DESCRIPTION

FIG. 1 is a top, front, right perspective view of a mobile electronic device;

FIG. 2 is a top, back, left perspective view thereof;

FIG. 3 is a bottom, back, left perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof; and,

FIG. 9 is a bottom view thereof.

The dashed broken lines depict portions of the mobile electronic device that form no part of the claimed design.

1 Claim, 9 Drawing Sheets
